UNITED STATES PATENT OFFICE

SAMUEL M. KASS, OF PHILADELPHIA, PENNSYLVANIA

PLUMBER'S BIB

Application filed February 23, 1925. Serial No. 10,987.

My invention relates to bibs or faucets. A purpose of my invention is to provide positive movement and reliable closure of a valve by a new combination of parts.

5 Further purposes will appear in the specification and in the claims.

I have chosen to illustrate my invention in several different forms, selecting forms that are convenient and efficient in operation 10 and which well illustrate the principles involved.

Figure 1 is a side elevation of a faucet embodying my invention.

Figure 2 is a section through the plane of 15 the paper of a portion of Figure 1.

Figure 3 is a reversed perspective view illustrating the valve lifting member used in Figure 2.

Like numerals refer to like parts in all 20 figures.

Describing in illustration and not in limitation and referring to the drawings,—

In Figure 1 I show nipple 6, union 7, 25 gooseneck 8, barrel 9, discharge nozzle 10, and operating handle 11.

The barrel is internally threaded at its rear end 12 to receive the forward end 13 of the gooseneck, and its forward portion 14 is of reduced bore. The valve seat 15 is 30 formed conveniently where the bore is reduced.

The valve 16 is preferably of rubber and is mounted upon the forward end of a carrier 17 that slides within the larger bore of 35 the barrel.

The carrier comprises a rear ring 18, a forward ring 19 and connecting bars or strips 20 between which are provided water spaces 21. I prefer on account of lightness to form 40 the front or lower portion of the carrier in the form of a ring as shown rather than a plate reducing its weight by providing openings 22 in it. Whichever form be used I prefer to attach it lightly to the valve member 16, where rubber is used by a prong 23 fitting into the valve. This prong will 45 preferably be omitted where the valve is of complete ball form or where metal is used.

The rear ring of the carrier provides a seat 50 24 against or within which rests one end of a

spring 25 whose opposite end bears against the carrier at the rear of the cavity formed. As shown it fits within a seat 26.

As shown in Figure 2 the lower portion of the barrel is annularly recessed from the 55 underside as at 27 to receive the outer portion 28 of an upwardly directed double sleeve 29 whose inner sleeve member 30 fits within the interior of the barrel discharge sleeve 31. This discharge sleeve 31 is spirally slotted as 60 at 32 to receive the inner end 33 of the handle 11 which is threaded into the outer portion 28 of sleeve 29.

The upper end of the sleeve 28 is shown 65 as flared and after the parts have been connected the lower end 34 of the skirt 35 upon the barrel is preferably spun inwardly to hold the parts against disconnection.

When the handle is turned the projecting 70 pin-like part 33 travels in the cam-like slot lifting the sleeve 29 and through the inner part 30 lifting the valve member 16 against the pressure of the water and against the pressure of the spring 25.

The cuts in the upper part of the inner 75 member 30 allow the water to pass freely while the valve member is lifted. The reverse rotary movement of the handle permits the valve to seat; in each seating movement the weight of the valve is assisted by 80 the flow of the water and the spring 25.

It will be obvious that as a result of my disclosure others skilled in the art will be able to produce forms using a part or all 85 of my invention but avoiding exact duplication. It is my purpose to include herein all such as come within the reasonable spirit and scope of my claim.

Having thus described my invention, what I claim as new and desire to secure by Letters Patent is:—

In a bib, a barrel providing a chamber having a valve seat at one end and of reduced internal diameter below the valve seat, a valve resting upon the valve seat, a valve carrier spring-pressed against the valve, the barrel being annularly grooved at the bottom to provide a cylindrical inner shell and an outer shell concentric therewith, an annular operating member entering the annu- 90 95

lar groove, spiral interconnection between the cylindrical shell and the operating member, valve-engaging connections moved by the operating member an enlargement on the 5 upper end of the operating member and a cooperating contraction at the lower end of the outer shell to prevent withdrawal of the operating member.
